UNITED STATES PATENT OFFICE.

RUSSELL H. NOGAR, OF DUNDEE, MICHIGAN.

DITCHING-PLOW.

SPECIFICATION forming part of Letters-Patent No. 404,424, dated June 4, 1889.

Application filed August 2, 1888. Serial No. 281,815. (No model.)

To all whom it may concern:

Be it known that I, RUSSELL H. NOGAR, a citizen of the United States, residing at Dundee, in the county of Monroe and State of Michigan, have invented certain new and useful Improvements in Ditching-Machines, of which the following is a specification, reference being had therein to the accompanying drawings.

This invention relates to new and useful improvements in ditching-machines; and the invention consists, first, in the peculiar construction of the ditching-plow; second, in the means for raising and lowering it; third, in the means for applying the draft; fourth, in the peculiar combination of the ditching-plow with the means for elevating the ground, and, fifth, in the peculiar construction arrangement, and operation of the elevator, all as more fully hereinafter described.

In the drawings which accompany this specification, Figure 1 is a side elevation of my improved machine as arranged for operation. Fig. 2 is a plan thereof, with the raising and lowering device of the ditching-plow removed. Fig. 3 is a central vertical longitudinal section through the carrier. Fig. 4 is a vertical central cross-section through the ditching-scoop. Fig. 5 is a detached perspective view of the lever for raising and lowering the plow. Fig. 6 is a detached perspective view showing the construction of the bed of the carrier. Fig. 7 is a cross-section thereof, and Fig. 8 is a detached perspective view of the plow-support for holding the plow out of operation.

A is the plow-beam.

B is the standard of the plow, secured to the rear end of the plow-beam.

C is a plow, or rather scoop, secured to the lower end of the standard in any suitable manner or formed integrally therewith; and this scoop is of the peculiar cross-section shown in Fig. 4—that is, having the portions *a*, *b*, and *c*, forming, respectively, the sides and the bottom, the side *a* of the scoop bulging outside of the standard, the bottom *b*, which connects therewith, having its deepest portion near the standard where it connects with the side *a*, and rising from there gradually in a curved line to form the side *c*, which is at a higher level than the side *a*, thus form-

ing a cross-section which in practice cuts a ditch deeper on the side of the standard, and with a sufficient clearance upon the side of the standard for the latter to pass into the ditch without impinging against the sides thereof.

D is a ground-wheel for guiding the forward end of the plow in the ditch. This is secured to the lower end of the standard E, the upper end of which has a suitable fixed connection F with a suitable draft-pole G.

H is a draft-iron obliquely secured between the rear end of the pole and the lower end of the standard of the ground-wheel, and this draft-iron is provided with a series of adjusting holes *d*, to which a draft clevis or hook *e* is adjustably secured, and to which the usual draft-apparatus *f*, for attaching two or more horses, is applied.

I is a vertical bearing secured to the forward end of the draft-pole and to one side thereof, and this bearing loosely embraces the standard E of the plow-wheel, to permit of raising or lowering the plow-beam thereon, while at the same time it forms the draft-connection between the plow-beam and the standard E.

The devices for raising and lowering the plow in and out of the ground consist of the lever J, which is fulcrumed on top of the plow-beam by means of the link-support *k*, which is pivotally secured to the plow-beam at *g* and carries the fulcrum *h* of the lever. The free end of this lever embraces the upper end of the standard between suitable shoulders or collars *i*, formed upon the upper end of the standard, and a stop formed by a suitable shoulder or collar *j* upon the lower end of the standard limits the lowest position of the plow-beam.

L is an adjusting-strap, to which the lever J is secured in its adjusted position by means of any suitable locking device, as ordinarily used for such purposes, and which may be under the control of the operator from his seat.

In the rear of the plow an inclined elevator-carrier, preferably consisting of a broad belt *M*, of leather, rubber, or other suitable material, is mounted in the following manner:

Within the bight of the scoop is journaled in suitable bearings the roller *N*, over which the forward end of the belt passes, while the

rear end of the belt passes over the roller or pulley O, which is at a higher level to give the necessary inclination to the belt to carry the dirt out of the ditch. This pulley O is mounted upon a two-wheeled truck, which consists of the axle Q, the wheels P, and the frames R, between which the pulley O is journaled.

S is a friction-pulley journaled in hangers T below the carrier-belt, and held in operative contact with the pulley O by means of the tension-rod T', which pass upward through the frame and are provided with the adjustable tension-springs U, by means of which the friction-roll S clamps the belt or carrier between the face of the friction-roller S and the pulley O, for the purpose of transmitting motion to the carrier from the pulley O.

Upon the shaft V of the belt-pulley O is mounted the grooved drive-pulley W at the side of the frame of the truck. The belt M of the carrier is supported between its ends by means of a frame, preferably constructed as shown in Fig. 6, wherein l is a bed-timber pivotedly secured at its forward end to the shaft K of the roller N and fixedly secured at its rearward end to the truck. l' are saddles secured upon the bed-timber, and m are slats or rods secured upon the saddles to form a concave grating for the support of the carrier. By means of suitable sides n and the bottom board o an inclosing-frame is formed for the under side of the carrier. A hinged incline p is secured between the forward end of the scoop and the forward end of the carrier to form an inclined passage for the dirt into the carrier. By hinging this incline on its forward end it may be lifted up to allow the removal of any dirt or obstructions accumulating below the forward end of the carrier. A discharge-spout q is mounted near the rear end of the carrier to receive and carry the dirt to one side.

v is a seat for the driver, supported upon the outriggers s, secured to the frame of the truck and projecting in proximity to the rear end of the plow. The rear end of the plow-beam is provided with the foot-lever t, hinged thereto, and a draft connection u pivotally connects the foot-lever with the truck.

In practice, the parts being arranged substantially as shown and described, the scoop is raised or lowered by means of the lever J, which extends in proximity to the driver's seat. By raising such lever it will be seen the forward end of the plow-beam is raised, and by depressing it the forward end of the plow-beam is lowered, and the scoop is thereby made to pass into the ground. The draft is communicated to the plow by means of the standard E, which loosely engages into the vertical bearing I at the forward end of the plow-beam, and thereby admits at the same time of adjusting the plow in or out of the ground. The ditch is formed corresponding to the shape of the scoop—that is, deepest on the side of the standard and with the necessary

clearance to prevent friction of the standard against the sides of the ditch. By drawing the plow alternately in opposite directions from one end of the ditch to the other the ditch will be alternately lowered upon opposite sides, and thus the proper form of ditch be obtained. It will be seen that by means of this construction no side draft upon the plow is obtained, as the work is done in the center of the draft.

From the scoop the ground dug up is discharged onto the carrier, and to obtain the proper motion to the carrier I use a wire rope Y, which I stretch alongside the ditch between suitable end supports Z, and extending beyond the ends of the ditch, and this wire rope I pass around the grooved pulley W in such direction as to impart the desired motion to the carrier in the forward progress of the plow.

The draft is conveyed from the plow-beam through the intermediate connections of the foot-lever t and connection u to the truck which carries the rear end of the carrier, and it will be seen that by shortening or lengthening said connection the driver has the means, independently of the front raising and lowering device, to direct the plow in and out of the ground. This he does by means of the foot-lever t, the rear end of which forms a suitable foot-rest, and by pressing thereon he shortens the draft-connection between the plow and the truck, thereby raising the point of the plow. Thus he can much better direct the operation of the plow in detail than he can by means of the raising and lowering device alone. At the same time it will be seen that this draft-connection carries the draft directly to the rear truck without bringing any downward draft on the plow, which would tend to carry it into the ground and would render the control of the driver over the plow difficult. In order to raise the plow sufficiently out of the ground to prevent its working in turning around or passing from one point to another, I provide the plow-beam with the loop w and the rear truck with the hanger y, and a pole or lever z of suitable size, as shown in Fig. 8, is then secured with its free end into the loop w and lifted up until its rear end engages into the hanger y, when the plow is raised out of the ground, a suitable hook or chain z being made to engage on the brace a' or other suitable point on the plow-frame to give a firm hold to the lever on the plow.

The draft-clevis being pivotally secured on the draft-bar H, allows of adjusting the draft up or down as the depth of the ditch progresses. By means of the friction device applied to the carrier-belt the carrier may be run with a large degree of slackness, which in this class of machines is a considerable advantage on account of the constant change in length of the carrier under the varying degrees of moisture or dryness. At the same time the tension of the spring compensates

adly for a variation in the thickness of the carrier-belt that may be caused by adhering soil.

What I claim as my invention is—

1. The combination, with the ditching-plow, of a carrier mounted on a truck at the rear of the plow and having a hinged connection at its forward end with the scoop or plow, and the adjustable draft-connection with the rear end of the plow-beam, said connection being pivoted at one end to the plow-beam, substantially as described.

2. In a ditching-machine, the combination, with the ditching-plow, of the carrier mounted on the truck at the rear of the plow and having pivotal connection at its forward end therewith, and the adjustable draft-connection between the rear end of the plow and said truck, said draft-connection being pivoted at one end to the plow-beam and under the control of the operator, substantially as described.

3. In a ditching-machine, the combination, with the ditching-plow, of a carrier pivotally secured at its forward end to the scoop or plow and mounted with its rear end upon the truck, and a draft-connection between said truck and the rear end of the plow in the line of draft, consisting of the foot-lever *t* and the draft-connection *u*, substantially as described.

4. In a ditching-machine, the combination of the following elements: the ground-wheel mounted on a vertical standard, the draft devices applied thereto, the plow-beam provided at its forward end with the vertical bearing engaging with the standard of the ground-wheel, the scoop or plow secured to the rear end of the plow-beam, the raising and lowering device mounted upon the plow-beam, the carrier pivotally secured at its forward end to the plow and mounted at its rear end upon the truck, and the adjustable connection between the rear end of the plow and the truck, said connection consisting of the foot-lever *t* and the draft-connection *u*, substantially as described.

5. The combination, with the plow of a ditching-machine, of the endless carrier pivotally secured at its forward end to the rear end of the plow and mounted at its rear end upon a truck, a carrier-pulley mounted upon the truck and to which motion is applied, and a friction-pulley mounted below such carrier-pulley and pressing the belt against the face of the carrier-pulley, substantially as described.

6. The combination, with the plow of a ditching-machine, of a carrier consisting of the endless belt *M*, secured at its forward end to the plow and mounted at its rear end upon a truck, the belt-pulley *O*, mounted in suitable bearings upon the frame of the truck, the adjustable friction-pulley *S*, mounted in contact with the belt-pulley, the shaft *V* of the belt-pulley, and the grooved drive-pulley *W*, substantially as described.

7. The combination, with the ditching-plow, the carrier mounted in the rear thereof and supported upon the truck, the drive-shaft *V* of the carrier, the grooved pulley *W* upon said drive-shaft, and the wire rope *Y*, the parts being arranged to operate substantially as and for the purpose described.

8. In a ditching-machine, the combination of the following elements: the ground-wheel *D*, the vertical standard *E*, carrying such ground-wheel, the draft-bar *H*, the draft-connection adjustably secured to the draft-bar, the plow-beam provided at the forward end with the bearing *I*, into which the standard *E* engages, the raising and lowering lever *J*, pivotally mounted on top of the plow-beam and engaging by its forward end with the standard *E*, the adjusting devices of that lever, the scoop *C*, mounted on the standard *B*, the endless carrier *M*, the roller *N*, mounted in the scoop of the plow, the truck upon which the rear end of the carrier is mounted, the carrier-pulley *O*, over which the rear end of the carrier-belt passes, the friction-pulley *S*, the drive-pulley *W*, and the seat *R*, mounted on the rear truck in proximity to the rear end of the plow, substantially as described.

9. In a ditching-machine, the plow consisting of the plow-beam, the standard secured thereto, and the scoop secured to the lower end of the standard and having the digging portions *a*, *b*, and *c*, substantially as described.

10. In a ditching-machine, the combination of the ditching-plow, the carrier pivotally secured to the rear end of the ditching-scoop and mounted with its rear end upon the truck, a flexible draft-connection between the plow and the truck, the loop *w*, secured to the plow-beam, the lever *z*, and the hanger *y*, substantially as and for the purpose described.

In testimony whereof I affix my signature, in presence of two witnesses, this 30th day of June, 1888.

RUSSELL H. NOGAR.
